WEATHER STRIP

Howard A. Smith, New York, N. Y.

Application June 11, 1937, Serial No. 147,743

4 Claims. (Cl. 20—69)

The invention relates to a weather strip and more especially to a double weather strip for double sash windows of the sliding type.

The primary object of the invention is the provision of a weather strip of this character, wherein it can be installed by unskilled labor and provides maximum protection from weather and assures the most efficient window operation, being economical in initial cost and assures years of satisfactory service, eliminating all fitting or grooving of sash to accommodate the strip and is susceptible of use on any thicknesses of a double-hung window without regard to the type of balancing arrangement for the sashes.

Another object of the invention is the provision of a weather strip of this character, wherein the same effects a double lock between the sashes of the double-hung type and the window frame or casing being readily mounted in place for service against weather elements and is possessed of durability and also can be manufactured and installed at a minimum expense.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is a fragmentary enlarged transverse sectional view through a window of the double sash sliding type showing the weather strip constructed in accordance with the invention installed.

Figure 2 is an end elevation of one of the component parts of the weather strip, being the double lock section thereof.

Figure 3 is an end view of another component part.

Figure 4 is an end view of still another component part.

Figure 5 is a fragmentary perspective view partly in section of the upper sliding sash showing the weather strip fitted therewith.

Figure 6 is a view similar to Figure 5 showing the lower sash with the weather strip fitted therewith.

Similar reference characters indicate corresponding parts throughout the several views in the drawing.

Referring to the drawing in detail, A designates generally a portion of a window casing or frame, B a portion of the upper sash and C a portion of the lower sash, respectively, these sashes being

of the sliding type and are of conventional kind.

At each vertical side of the window casing or frame A in substitute for the usual parting strip or stop (not shown) fitted therein is a double lock strip-like guide section formed from a single length of metallic sheet material bent on itself to provide an intermediate parting web 10 of substantially U shape in cross section and outer folded guide cheeks 11, these being spaced from the web 10 uniformly and form relatively deep channels 12 therebetween while the outer fold 13 of each cheek 11 following the free edge of the said fold is outwardly struck or offset at 14 to effect resilient clamping portions 15 functioning as jaws so that when the section creating the web 10, cheeks 11 and channels 12 is inserted in the parting strip groove 16 formed in the vertical side of the window casing or frame A, the said section will be frictionally held within the said groove and such section is coextensive with each side of the window casing or frame sash opening therein for the fitting of said section in the window casing or frame.

Secured to the meeting stiles 17 of the upper and lower sashes B and C are male and female spring snap interlocking tongue and groove strip-like sections 18 and 19, respectively, the tongue section 18 being formed with a flange extension 20 at right angles thereto for corner fitting the stiles 17 and adapted to accommodate fasteners 21 securing the said sections to the stiles 17 at the confronting sides thereof of the top and bottom sashes. The sections 19 have the folded guard flanges 22 which are slidably accommodated in the channels 12 formed in the guide sections fitting each channel or groove 16 in the vertical side of the window casing or frame A. Each groove section 19 at opposite ends thereof, its length being in accordance with the length of the stiles 17 of each sash, has capping the same terminal boxes 23, each formed with an attaching tongue 24 accommodating a fastener 25 driven into the stile 17 and an interlocking ear 26 interfitting and pocketed by the ends of the tongue section 18. In this manner the sections 18 and 19 are made fast to and carried by the stiles 17 of the upper and lower sashes B and C, respectively, the meeting cross rails 27 of the said sashes being cut away at 28 for the insetting of the terminal boxes 23 upon said sashes.

The folded flanges 22 projecting from the stiles 17 of the upper and lower sashes B and C slidably fit in the channels 12 in the guide sections of the weather strip and the latter effects a double lock between the window casing or frame and the said

50

55

sashes and in this manner the weather strip creates or provides a double weather lock between the window casing or frame and the sashes, the weather strip being simple and is readily and 5 easily installed by unskilled labor and when installed affords maximum protection from weather elements as well as most efficient window operation.

To attach my invention to a typical form of 10 window having sliding sashes, the sashes are first moved from the frame and the parting web 10 substituted for the usual parting strip within the parting strip groove 16. The sections 18 are secured to the sides of the rails 17 of the upper 15 and lower sashes B and C. The upper and lower sashes are then inserted within the window frame in the usual manner, the cheeks 11 of the web 10 engaging the adjacent faces of the sections 18. In this position of the parts and with reference 20 to the upper sash B, the flanges 22 of the sections 19 are inserted within the channels 12 below the upper sash and moved upwardly within the channels 12 for adjustment opposite the adjacent face of the rail. The offset arcuate shaped portions of the sections 19 telescope over similar shaped portions of the sections 18. The terminal boxes 23 are then applied over each of the ends of the strips to maintain them in connected relation. Likewise, the sections 19 are secured to the 25 sections 18 of the lower sash in a similar manner, the flanges 22 of the sections 19 being inserted in the channels 12 above the lower sash and moved downwardly therein for connection with the sections 18. A reverse operation of the 30 sections 18 described parts permits of ready removal of one or both of the sashes from the frame for any desired purpose.

What is claimed is:

1. The combination with a window frame having double sliding sashes, of a weather strip comprising a double grooved guide strip counterseated vertically in each side of the window frame in substitute for a parting strip, spring interlocked tongue and groove male and female guard strip sections carried by the sashes and slidably engaged with the double grooved guide section, said female section adapted for independent sliding movement relative to said guide strip and male section whereby to permit assembling and disassembling of the coacting parts of the combination, and terminal boxes attached to the sashes and interfitted at and with the ends of the said guard strip sections for capping the ends thereof.
2. The combination with a window frame having double sliding sashes, of a weather strip comprising a double grooved guide strip counterseated vertically in each side of the window frame in substitute for a parting strip, spring interlocked

tongue and groove male and female guard strip sections carried by the sashes and slidably engaged with the double grooved guide section, said female section adapted for independent sliding movement relative to said guide strip and male 5 section whereby to permit assembling and disassembling of the coacting parts of the combination, terminal boxes attached to the sashes and interfitted at and with the ends of the said guard strip sections for capping the ends thereof, and folded guard flanges extending from one of the last-mentioned sections and slidably accommodated within its companion groove in the guide section.

3. The combination with a window frame having 15 double sliding sashes, of a weather strip comprising a double grooved guide strip counterseated vertically in each side of the window frame in substitute for a parting strip, spring interlocked tongue and groove male and female guard 20 strip sections carried by the sashes and slidably engaged with the double grooved guide section, said female section adapted for independent sliding movement relative to said guide strip and male section whereby to permit assembling and 25 disassembling of the coacting parts of the combination, terminal boxes attached to the sashes and interfitted at and with the ends of the said guard strip sections for capping the ends thereof, folded guard flanges extending from one of the last- 30 mentioned sections and slidably accommodated within its companion groove in the guide section, and spring jaws formed on the guide section for frictional fastening of the latter in the window frame.

4. The combination with a window frame having 35 double sliding sashes, of a weather strip comprising a double grooved guide strip counterseated vertically in each side of the window frame in substitute for a parting strip, spring interlocked tongue and groove male and female guard 40 strip sections carried by the sashes and slidably engaged with the double grooved guide section, said female section adapted for independent sliding movement relative to said guide strip and male section whereby to permit assembling and 45 disassembling of the coacting parts of the combination, terminal boxes attached to the sashes and interfitted at and with the ends of the said guard strip sections for capping the ends thereof, folded guard flanges extending from one of the last- 50 mentioned sections and slidably accommodated within its companion groove in the guide section, spring jaws formed on the guide section for frictional fastening of the latter in the window frame, 55 and fasteners for the male guard sections, securing them to the sashes.

HOWARD A. SMITH.
